UNITED STATES PATENT OFFICE

MORRIS CHODORKOW AND ROBERT HARVEY, OF NEW YORK, N. Y.

DESIGN FOR TRIMMING FOR TRAVELING-BAGS, SUITCASES, OR SIMILAR ARTICLES.

45,251.

Specification for Design.

Patented Feb. 17, 1914.

Application filed November 25, 1913. Serial No. 803,056. Term of patent 7 years.

To all whom it may concern:

Be it known that we, MORRIS CHODORKOW and ROBERT HARVEY, a citizen of the United States and a subject of the Czar of Russia, respectively, residing at the city of New York, in the county of New York and State of New York, have invented a new, original, and ornamental Design for Trimmings for Traveling-Bags, Suitcases, or Similar Articles, of which the following is a specification, reference being had to the accompanying drawing, forming part thereof.

The figure is a perspective view of a trimming for traveling bags, suit-cases or similar articles, showing our new design.

We claim:

The ornamental design for a trimming for traveling bags, suit-cases or similar articles, as shown.

MORRIS CHODORKOW.
ROBERT HARVEY.

Witnesses:

SIGMUND HERZOG,
S. BIRNBAUM.
